UNITED STATES PATENT OFFICE.

EDGAR F. PRICE, OF PORT CHESTER, NEW YORK, ASSIGNOR TO ELECTRO METALLURGICAL COMPANY, OF NEW YORK, N. Y., A CORPORATION OF WEST VIRGINIA.

ELECTRIC FURNACE.

1,239,214.

Specification of Letters Patent. Patented Sept. 4, 1917.

Application filed February 1, 1917. Serial No. 145,870.

To all whom it may concern:

Be it known that I, EDGAR F. PRICE, a citizen of the United States, residing at Port Chester, in the county of Westchester 5 and State of New York, have invented certain new and useful Improvements in Electric Furnaces, of which the following is a specification.

This invention relates to electric furnaces, 10 the primary object of the invention being to provide in connection with such furnaces a hearth or bed which will not be subject to rapid destruction by oxidation or other influences. In the particular embodiment 15 of the invention chosen for illustration, the hearth constitutes one of the furnace electrodes or circuit terminals, but the invention is not restricted to use in furnaces of this particular type.

20 The accompanying drawings represent an illustrative embodiment of the invention. In said drawings—

Figure 1 is a vertical sectional view of a furnace constructed in accordance with my 25 invention; and

Fig. 2 is a horizontal section thereof on lines II—II of Fig. 1, a portion only of the overlapping plates being shown in place upon the base of the furnace.

30 Referring to the said drawings, 1 represents the refractory walls of the furnace, and 2 the base, which may be constructed of cast iron. Preferably the base comprises several sections or segments, and is cooled 35 by a spray of water introduced through any suitable distributing device 3. Any equivalent cooling means may of course be provided. 4 represents a depending electrode, of which any desired number may of course 40 be employed.

A number of metal sheets or plates 5 are disposed upon the metal base 2, and preferably in direct contact therewith. These are usually of sheet iron which may be of 30 gage or heavier, and are laid in an overlapping or shingle-like series, as clearly shown in the figures. The usual carbon hearth 6 is laid upon these plates, comprising in the particular construction illustrated 45 a number of blocks or bricks of carbon or carbonaceous material so disposed as to break joints. Electrical connections may

be made, as diagrammatically indicated at 7, to the base and depending electrode, respectively.

In electric furnaces of the type referred to herein it is essential that the base should be adequately cooled; and this in turn renders it practically desirable to use a segmental base construction, in order to avoid 60 the breaking which would otherwise be liable to occur under unequal heating and temperature changes. This ordinarily leads to a rather rapid destruction of the overlying carbon hearth, owing largely to oxidation by air and moisture entering from below. I have found however that a much longer life is assured to the hearth by providing between it and the metal base of the furnace the series of overlapping, relatively 65 thin metal sheets or plates as above described. These sheets are pressed into contact with each other by the weight of the hearth, and under these conditions have been found to be practically effective in preventing 70 the destructive action of air and moisture.

I claim:

1. In an electric furnace, the combination of a base, a hearth or bed, and a series of 80 overlapping metal sheets interposed between said base and hearth.

2. In an electric furnace, the combination of a cast-metal base, a hearth or bed of carbonaceous material, and a series of overlapping metal sheets interposed between 85 said base and hearth.

3. In an electric furnace, the combination of a segmental metal base, cooling means therefor, a hearth or bed, and a series of 90 overlapping metal sheets interposed between said base and hearth.

4. In an electric furnace, the combination of a segmental base, cooling means therefor, a hearth or bed of carbonaceous material, 95 and a series of overlapping metal sheets interposed between said base and hearth.

In testimony whereof I affix my signature in presence of two witnesses.

EDGAR F. PRICE.
